CIRCUIT BREAKER CONTACT

Arthur S. Caswell, Philadelphia, Pa., assignor to
 I-T-E Circuit Breaker Company, Philadelphia,
 Pa., a corporation of Pennsylvania

Application April 4, 1944, Serial No. 529,439

2 Claims. (Cl. 200—166)

1

My present invention relates to contact members, and more particularly to the stationary contact unit which provides in simplified form both for the main and arcing contact surfaces and, at the same time, is so arranged that a direct connection is made from the contact elements to the current carrying bus without the necessity of flexible pigtails or other types of easily worn out connecting members.

Also, my invention contemplates that the very elements which ensure proper current carrying relationship between the stationary contact members and the bus to which they are connected also ensure proper engagement between these stationary contact members and the movable contact unit.

An important object, therefore, of my invention is the arrangement of contact members so that a direct current carrying connection is provided between the contact member and the bus on which they are mounted without the necessity for flexible pigtails or other connecting elements which are usually subjected to wear and frequently require replacement and repair.

Another and important object of my invention also is the provision of biasing means with respect to the main and arcing contacts of a switch structure, which biasing means have a two-fold purpose: (1) to provide a direct current carrying connection between the main and arcing contacts and the bus on which they are mounted and (2) to provide appropriate contact pressure between these main and arcing contacts and the complementary contacts.

These and many other objects of my invention will become apparent in the following description and drawings in which:

Figure 1 is a cross-sectional view of a pair of complementary contact units embodying the principles of my invention.

Figure 2 is a cross-sectional view taken on line 2—2 of Figure 1.

Figure 3 is a cross-sectional view illustrating a modified form of my invention.

Figure 4 is a cross-sectional view taken on line 4—4 of Figure 3 looking in the direction of the arrows.

Figure 5 is an expanded view in perspective of the contact structure of Figures 3 and 4.

Figures 6, 7 and 8 are schematic views showing respectively the closed, partially open and open position of a circuit breaker embodying the contact elements of Figures 1 and 2.

Referring now to Figures 1 and 2, I have here

2

shown a stationary contact unit 10 constructed in accordance with the principles of my invention and a complementary movable contact member 12.

In the specific embodiment here shown, it is intended that the complementary contact member 12 be the movable contact and that it have an axial motion toward and away from the stationary contact structure 10. It will be obvious, of course, that in appropriate cases the contact member 12 may be the stationary contact unit, while the contact structure 10 be made the movable unit having the axial movement toward and away from the contact 12. It is preferred, however, that the structure 10 in this instance be the stationary one.

The stationary contact structure 10 comprises a main current carrying member 11 on which are secured the various elements of the contact.

20 The main current carrying member 11 may, of course, be a direct extension of the bus or an extension of a back connection stud which is specifically formed to accommodate the various members. The front end of the current carrying member 11 is provided with a transverse slot 13 at the base of which a pair of recesses 15 and 16 are provided in order to position the compression springs 18 and 19.

25 A pair of main contact housings 20 and 21 are secured to the front end of the current carrying member 11 on opposite sides of the transverse slot 13 by means of bolts 25 and 26 which pass through a portion of each of the respective housings 20 and 21 into tapped openings in the front end of the current carrying member 11.

30 The inner walls of the housings 20 and 21 are each respectively arranged to provide shoulder extensions 28 and 29 extending somewhat over the opening of the transverse slot 13.

35 A stationary arcing contact member 30 is arranged so that it may slide in and out of the space 31 between the opposite housings 20 and 21.

40 The arcing contact member 30 is a member of 45 substantially rectangular cross-section having at its outer surface an arcing contact tip 32 and having at its innermost end a pair of opposite flanges 34 and 35 which are designed (at the end of the path of travel of the arcing contact member 30) to bear against the flanges 28 and 29 to prevent further outward movement of the arcing contact member 30.

45 Arcing contact member 30 is provided with a pair of recesses 38 and 39 to receive the opposite ends of the compression springs 18 and 19. The

55

recesses 38 and 39 are thus in axial alignment with the recesses 15 and 16 in the end of the main current carrying member 11.

The arcing contact member 30 is, of course, of conductive material; while the contact tip 32 is of an appropriate arc resisting material.

The opposite flanges 34 and 35 of the arcing contact member 30 are in sliding fit with the side walls 40 and 41 of the slot 13.

An appropriate current carrying connection from the arcing contact 30 to the current carrying member 11 is provided through the main contact members 50 and 51 hereinafter described.

It will, however, at present be clear that as the movable contact member 12 moves axially so that the movable arcing contact tip 43 moves into engagement with the stationary arcing contact tip 32, the arcing contact member 30 will be pushed up against the compression of the springs 18 and 19. At this point, the main contact surfaces 53 and 54 of the movable contact 12 will move respectively into engagement with the contact surfaces 55 and 56 of the main stationary contacts 50 and 51.

Each of the housings 20 and 21 is provided with transverse slots 60 and 61 forming a chamber therein.

The walls of the housings 20 and 21 are so formed as to provide reentrant ledges or flanges 62, 62 and 63, 63 at the open ends of each of the transverse slots 60 and 61.

The main contact members 50 and 51 are each provided with a pair of recesses 70, 70 and another pair of recesses 71, 71 normal to the first pair of recesses 70. Each of the pair of recesses 70 in each of the main contact members 50 or 51 has its longitudinal axis normal to the main contact surfaces 55 or 56. Consequently, compression springs 73, 73 in each of the recesses 70, compressed between the base of each recess 70 and the base 75 of each slot, drive the respective contact members 50 and 51 inwardly toward the space 31.

Shoulders 77, 77 on each of the respective contact members 50 and 51 bear against respective flanges 62 and 63 of the housings 20 and 21 to limit the movement of the contact members toward the space 31. By this means, the contact members 50 and 51 are given appropriate contact pressure; that is, the springs 73 bias these contacts toward engagement with the main contact surfaces 53 and 54 of the movable contact 12. Thus, when the movable contact 12 moves longitudinally into the space 31 between the main contact housings, first the arcing contact tip 43 engages the stationary contact tip 32, and on continued movement of the contact member 12, the stationary arcing contact member 30 is pushed back into the slot 13.

As the movable contact member 12 thus continues to move, the main contact surfaces 53 and 54 thereof move respectively into engagement with the main stationary contact surfaces 55 and 56.

On completion of the closing movement of the movable contact member 12, the entire surface of each of the main stationary contact surfaces 55 and 56 is pressed respectively against the main contact surfaces 53 and 54. Appropriate contact pressure is obtained by means of the compression springs 73, as above described.

In order now that proper contact be made between the main contact members 50 and 51 and the current carrying member 11, compression springs 80, 80 are provided in each of the recesses

71 of each of the main contact members 50 and 51, each of these springs 80 being compressed between the base of the recess 71 in which it is located and the wall 82 of the housing. The compression springs 80, therefore, drive the movable contact members 50 and 51 firmly toward the right and thus against the wall 85, 85 of each of the housings 20 and 21.

By this means, therefore, the contact members 50 and 51 are brought into close contacting engagement with the inner wall 85 of each of the housings 20 and 21; and since each of the housings 20 and 21 is itself closely held by means of the bolts 25 and 26 against the face of the main current carrying member 11, a good current carrying path is provided from the main contact surfaces 55 and 56 to the current carrying member 11.

The utilization of the springs 73 and 80 which operate in directions normal to each other thus provides for good contact (in the case of springs 73) between the stationary and movable main contact surfaces and (in the case of springs 80) for good contact pressure between the main stationary contact members and the current carrying member 11.

By this means, therefore, the necessity for pigtail connections between the main stationary contact member and the main current carrying member is obviated. The connection between these members is obtained by simple spring pressure and by means of parts which are not subjected to flexing, bending, rotative tearing or corrosive forces.

Similarly, on contact separation, the current carrying path from the arcing contact member 30 to the main current carrying member 11 is also provided by means of the main contact members 50 and 51 which, by means of the spring 73, are pressed tightly against the sides of the arcing contact member 30 and which, therefore, in the manner previously described, establish a current carrying path to the main current carrying member 11.

During the opening of the circuit breaker when the movable contact member 12 moves down, the main contact surfaces 53 and 54 slide respectively with respect to the stationary main contact surfaces 55 and 56. During this sliding movement, the sides of the stationary arcing contact move progressively into engagement with the stationary main contact surfaces 55 and 56.

When the main contact surfaces 53 and 54 of the movable contact member move out of engagement with the main stationary contact surfaces 55 and 56, the arcing contact member 30 still has room for additional downward sliding motion, so that for this brief period of time during the completion of the downward movement of the arcing contact member 30, only the arcing contact surfaces 43 and 32 are in engagement.

When the arcing contact member 30 reaches its limit of movement, that is when the flanges 34 and 35 move against ledges 28 and 29, the arcing contact member 30 is halted and the arcing contact surfaces 32 and 43 separate on continued downward movement of the movable contact 12.

The arc is then drawn between the arcing contact tips 32 and 43 which are designed to withstand the arc, while the main contact surfaces 53 and 54 of the movable contact 12 and the main contact surfaces 55 and 56 of the stationary contact 10 are thus protected.

The slots 13, 60, and 61, which define the various chambers in which the arcing contact and the main contact members move, are fully en-

5

closed (except at the contact ends) by means of the pair of side plates 90 and 91 which are positioned on each side of the stationary contact member, as shown in Figure 2, to close off the ends of these slots.

The side plates 90 and 91 may be provided with flanges 92 and 93 respectively which serve as additional securing members to maintain the housings 20 and 21 of the main contacts in appropriate position.

The main current carrying member 11 is provided with appropriate recesses 94 and 95 so that the side plates 90 and 91 may be properly positioned with respect thereto to present a flush appearance.

The plates 90 and 91 may be secured in position in any suitable manner as, for instance, by bolts which engage not only the main current carrying member 11 but also the sides of the respective housings 20 and 21.

The side plates 90 and 91 simplify the replacement and repair of the main and arcing contacts. On removal of the side plates 90 and 91, the main contact members 50 and 51 slide out from the ends of their respective slots 60 and 61.

Similarly, an appropriate tool may then be entered into the slot 13 from the side to compress the springs 18 and 19 so that they may be withdrawn from the recesses 15 and 16, and so that the arcing contact member 30 may be slid out sideways.

When all of the elements are in position, they are secured in appropriate position by means of the side plates 90 and 91.

By this means, a proper sequential operation is obtained during the separation of the contacts so that the main contacts separate first and the arcing contacts separate last.

It is obvious, of course, that the stationary and movable contacts may have any appropriate shape which may be suitable to the particular purpose. Thus, for instance, as seen in Figure 2, the movable contact member 12 is a substantially flat member having a single arcing tip 43. The arcing contact member 30 need not necessarily be a single member of rectangular cross section; it is, in fact, preferred that it be two separated members, each of the said members being similar in form and half the width of the movable contact member 12, and each of said members being separately biased by its respective spring 18 or 19. This will further ensure appropriate arcing contact pressure.

Similarly, each of the main stationary contacts 50 and 51 may be a single member extending through the entire slot 60 or 61; or they may be separate members each similar in form and in operation so that a pair of similar members on each side will further ensure main contact pressure; it is in fact preferred for the purpose of obtaining appropriate contact pressure in case of possible unevenness of the surfaces that two or more contact members 50 or 51 be used alongside each other on each side.

In Figures 3, 4 and 5, I have shown a slight modification of the structure herein described wherein only one spring is needed with respect to the main stationary contacts to obtain both appropriate contact pressure between the complementary contacts and to ensure a proper current carrying path from the main stationary contacts to the current carrying member.

In this case, the stationary contact structure 110 is mounted as a unit in any suitable manner between side plates 111a and 111b, which are

6

extensions of the main current carrying member.

The stationary contact member 110 is itself a single unit which may be mounted as a complete unit on the current carrying member between 5 the side plates 111a or 111b or removed as a complete unit.

The stationary contact member 110 comprises a pair of opposite main contact housings 120 and 121 which are secured in any suitable manner as, for instance, by the bolts 125, 125 to the U-shaped bracket 145 having the flange extensions 141, 141 to receive the bolts 125.

Each of the housings 120 and 121 is provided with a front plate 185, 185 of conductive material secured thereto in any appropriate manner as, for instance, by the bolts 125a. The end of each of these plates 185 and the sides of each of the housing members 120 and 121 are provided with tapped openings 190, 190 to receive bolts 20 191, 191 which pass through the extensions 111a and 111b of the main current carrying member for the purpose of securing the main stationary contact member 110 to the main current carrying member.

25 The housing member 120 (as well as the housing member 121) and the plate 185 each define an open ended chamber 160, 160 in which the respective main stationary contacts 150, 150 are housed.

30 Each of the plates 185 is provided, adjacent the end thereof which defines the open space 131 between the opposed main stationary contacts, with a shoulder 163.

Each of the main contact members 160 is also 35 provided with an extension 177 which bears against the shoulder 163 and prevents the contact from being completely removed from the chamber 160 under the bias of the compression spring 173.

40 Compression spring 173 is mounted in a recess 171 in a wall of the housing 120 (or 121) and bears against the base of the said recess. The opposite end of the compression spring 173 enters a recess 172 in the main stationary contact 150. 45 Recesses 172 and 171 are in axial alignment so that the spring 173 bears against the base of each of the recesses 172 and 171.

Each of the main contacts 150 is provided with a main contact surface 155. Each of the extensions 177 of each of the main contacts 150 is provided with a contact surface 176.

It will be noted that the angle of the spring 173 is such that it is substantially 45° to each of the contact surfaces 155 and 176.

Consequently, it will be noted that the compression spring 173 has two components; it drives each of the main contact members 150 toward the right so that each of the contact surfaces 176 bears tightly against the inner surface of the plate 185, and, also, it drives each of the main contact members 150 toward the space 131 to obtain appropriate contact pressure.

By this means, therefore, the single spring 173 of Figures 3 to 5 performs the function of the two springs 71 and 73 of Figures 1 and 2.

The arcing contact member 130 moves in the space 131 between the opposite main contact surfaces 155. The upper end of the arcing contact 70 130 rides in the chamber 113 defined by the bracket 145 and the oppositely adjacent surfaces of the housings 120 and 121.

A compression spring 118 bears at one end against the inner surface of the base of the U-shaped bracket 145, and at the opposite end

enters the recess 138 in the arcing contact member 130.

The arcing contact member 130 is provided with opposite flanges 134 and 135 which bear against shoulders 128 and 129 of the housings 120 and 121.

Flanges 134 and 135 thus limit the downward movement of the arcing contact member 130.

As is shown in Figure 4, the arcing contact member 130 is made up of two separate units 130a and 130b. A separate spring 118 drives each of these units outwardly toward the right.

Proper current carrying pressure between the arcing contact units 130a and 130b and the plate extensions 111a and 111b is obtained by means of the transverse compression springs 196. These transverse compression springs 196 are positioned in opposite coaxial recesses 197, 197 in each of the opposite units 130a and 130b and bear against the bases of these recesses to drive the arcing contact units 130a and 130b apart. The outer surfaces of the arcing contact units 130a and 130b are thus driven firmly against the plates 111a and 111b in order to obtain appropriate contact carrying pressure between them.

Each of the main contact members 150 on each side of the space 131, as is shown in Figure 5, may be a compound unit consisting of two separate members which may likewise be driven apart, so that the side surfaces bear against the plates 111a and 111b by means of an exactly similar arrangement of springs 196 positioned in exactly similar recesses 197. Although this is desirable and preferred, it is not absolutely essential since the spring 173 has the dual function of maintaining not only contact pressure between the contacts but current carrying pressure between the members 150 and the plate 185 which, in turn, is bolted to opposite plates 111a and 111b.

Likewise, it is clear that, as was described in connection with Figures 1 and 2, the arcing contact member 130 may be maintained in appropriate current carrying relation with the plates 111a and 111b by reason of the fact that the main contact surfaces 155 bear against the sides of the arcing contact 130 as the movable and stationary contacts separate.

As previously described, the arcing contact members 130 each have an arcing tip 132 which engages a similar arcing tip 143 on the movable contact member 112.

The movable contact member 112 is also provided with main contact tips 153, 153 to furnish an appropriate current carrying engagement with the contact tips 155 of the stationary main contacts 150.

During the closing of the circuit breaker of Figures 3 to 5, as the movable contact member 112 moves up, the arcing contact tip 143 first engages the arcing contact tip 132 and the arcing contact 130 is moved up against the compression of spring 118. On continued upward movement of the movable contact 112, main movable contact tips 153 move into engagement with the stationary main contact tips 155 to complete the engagement of the respective contact units 112 and 110.

On tripping of the circuit breaker, the movable contact 112 moves downward. As it moves downward, the arcing contact tips 132 and 143 continuously remain in engagement since the compression spring 118 drives the arcing contact member 130 to follow the movable contact 112.

The movable contact tips 153, however, slide with respect to the stationary contact tips 155.

When the flanges 134 and 135 strike the extending shoulders 128 and 129 of housings 120 and 121, the arcing contact 130 is brought to a halt, and on continued movement with the movable contact 112, an arc is drawn between the arcing contact tips 132 and 143, while the main contact tips 153 and 155 are protected.

In this particular embodiment, it is again pointed out that the single spring 173 on each of the stationary main contact members 150 has the dual function of maintaining proper contact pressure and of maintaining a proper current carrying path between the contact member 150 and the current carrying member of which the plates 111a and 111b are extensions.

This dual function is accomplished by reason of the fact that the spring 173 is set at such an angle with respect to the contacting surfaces 176 and 155 as to have two components driving each of these respective contact surfaces in the proper direction to maintain proper current carrying relationship between those surfaces and their complementary elements.

Here again, the utilization of the spring pressed stationary contact members, which are spring pressed not only into engagement with the complementary contact but also in engagement with the current carrying member on which they are mounted, eliminates the necessity for pigtail connections or other types of connections which may then break, tear, or become corroded in operation. Consequently, the cost of maintenance and repair on these contacts is greatly decreased.

Likewise, the contact structure of Figures 3 to 5 is readily removable and the elements thereof are readily replaceable.

The unit 110 of Figure 3 is a single integrated unit which may be inserted between the extensions 111a and 111b and bolted thereto and which may as readily be removed therefrom.

The only specific operation necessary other than the manipulation of the necessary bolts is to compress together the arcing contact elements 130a and 130b so that they may slide between the plates 111a and 111b. Once the unit 110 has been removed from between the plates 111a and 111b, each of the elements of the structure 110 is readily acceptable for examination, replacement, and repair.

It is only necessary to remove the bolts 125 and 125a to completely expose every single part of the unit; and conversely, it is only necessary to arrange the unit in the form shown in Figure 5 and replace the bolts 125 and 125a to reintegrate the structure 110 of Figure 3, then the structure as a whole may be placed between the current carrying plates 111a and 111b and thus be integrated with the circuit breaker.

In Figures 6, 7 and 8, I have shown schematically, the manner in which my novel contact members may be utilized in an air blast circuit breaker of the type shown in applications Serial Nos. 483,387 and 410,260 of William M. Scott, Jr., and of William M. Scott, Jr., and Otto Jensen, filed April 17, 1943, and September 10, 1941, respectively, and assigned to the assignee of this application.

The contact members shown in Figures 1 and 2 are here used.

The movable contact member 12 is here shown as an extension of a piston 203 which moves in a cylinder 202 and is biased toward raised or contacting position by a spring 201. The cylinder

202 and the entire contact structure is mounted on the air tank 204. On occurrence of predetermined circuit conditions, air in the valve dome 210 is released to permit the tank air pressure to open valve 207 so that air may flow under pressure through passage 208 into cylinder 202. Air pressure drives down piston 203 to open the contacts, while the air reaches up past the contacts in the arc chute 205 to exhaust through the vents 206. This operation is more fully described in the applications above referred to.

The upper main stationary contacts 51 and 50 and arcing contact 30 are connected to the upper connection stud 214.

The lower main stationary contacts 51 and 50 operate and are constructed in the same manner as do the upper ones and are connected to the lower connection stud 215.

The movable contact 12 acts as a bridge between the upper and lower contacts. The circuit is closed in Figure 6 and open in Figure 8. The intermediate secondary contacts 251 and 250 are spring biased inwardly to the center of the arc chute by means of springs 273, bearing between the base 212 of their respective housing 221 and 220 and the bases of the intermediate contact members. They serve further to protect the main upper contact surfaces.

It may thus be seen that my invention may readily be incorporated in existing types of circuit breakers.

In the foregoing, I have described my invention and the basic principles thereof only in connection with the specific preferred embodiments. Many variations and modifications of these preferred structural embodiments within the spirit of my invention should now be obvious to those skilled in the art. Accordingly, I prefer to be bound not by the specific disclosures herein, but only by the appended claims.

I claim:

1. In a circuit interrupter, an electrically con-

ductive contact block having a substantially central opening; additional openings in said contact block on opposite sides of said central opening; contact members mounted in said additional openings in said contact block on opposite sides of said central opening; means biasing each of said contact members into engagement with a wall of its opening in said contact block; said contact block bridging said contact members on opposite sides of said opening; additional means biasing said contact members toward each other into said central opening; and stop elements for limiting the movement of said contact members into said central opening.

2. In a circuit interrupter, an electrically conductive contact block having a substantially central opening; an additional opening communicating with the central opening; a contact member mounted in said additional opening on said contact block; means biasing said contact member into engagement with the wall of said additional opening in said contact block and into said central opening; and stop elements for limiting the movement of said contact members into said central opening.

ARTHUR S. CASWELL.
